UNITED STATES PATENT OFFICE.

CHARLES S. NORRIS, OF TROY, OHIO.

NUT-LOCK.

No. 894,041.

Specification of Letters Patent.

Patented July 21, 1908.

Application filed January 22, 1908. Serial No. 412,066.

To all whom it may concern:

Be it known that I, CHARLES S. NORRIS, a citizen of the United States, residing at Troy, in the county of Miami and State of Ohio, 5 have invented certain new and useful Improvements in Nut-Locks, of which the following is a specification.

My invention relates to improvements in nut-locks, and the object of my invention is 10 to provide a nut lock which will be simple in construction and effective in operation.

My invention consists in the constructions and combinations of parts hereinafter described and set forth in the claims.

15 In the accompanying drawings Figure 1 is a sectional view of a device embodying my invention; Fig. 2 is a section on the line $x-x$ of Fig. 4; Fig. 3 is a detail of the locking screw head or cap; Fig. 4 is a plan view of the device; Fig. 5 is a detail of the connecting pin between the lock and the nut.

Like parts are represented by similar characters of reference in the several views.

In the example of this invention which I 25 have shown in the drawings I have illustrated it as applied to an ordinary bolt, although it will be obvious that it can be applied to an axle or any other device where it is desired to lock the nut. In the said drawings, a represents a bolt and b its nut which is screwed on to the end of the bolt by right hand threads in the ordinary manner. The end of the bolt is provided with a screw threaded socket, a^1 , the threads of which are left handed and into 30 this socket is screwed the stud, c^1 , of a locking head or cap, c . The locking head, c , is provided with a longitudinal perforation, c^2 , and the nut, b , is provided with a series of longitudinal perforations, b^1 , adapted to 35 register with the perforation, c^2 . In the drawings I have shown the nut, b , provided with four openings or perforations but a greater number of these may be employed if desired.

40 45 When the nut, b , has been screwed to its proper position on the bolt or other device to which it is to be applied, the studded cap or head, c , will be screwed into the socket, a^1 , as far as possible until its opening, c^2 , registers 50 with one of the openings, b^1 , of the nut and then a pin, d , will be inserted through the re-

spective openings. This pin, d , is in the nature of a cotter pin, the respective halves being offset slightly as at d^1 , these offset portions being placed at a point in the pin so as 55 to lie between the head and nut when the pin is in position and thus act in the nature of a spring stop to hold the pin in its position; the spring of the pin permitting the insertion of this offset portion through the openings in 60 the head, c , in a manner which will be well understood. After the pin is in position, its ends, d^2 , may be bent over so as to further 65 clench the pin in its position. In order to provide for the clenching or unclenching of the ends of the pin I preferably provide the nut, b , about its screw-threaded opening with a boss or shoulder b^2 , so that when the nut is screwed up against the part to which the bolt is applied a space will be left between said 70 part and the main body of the nut to afford access to the ends of the pin.

By the construction described it will be seen that an effective lock is provided for the nut which may be easily and quickly 75 removed and replaced at any time without destroying either the nut, lock or pin. Also by this construction a wide range is provided for the adjustment of the nut with reference to its lock for the reason 80 that by simply providing different sized pins the nut may be separated from the locking head any distance within the range of the length of the pin.

I have shown the off-set at, d^1 , Fig. 4, 85 and have described same as being formed before the pin is inserted in position, but it is obvious that an off-set might be formed in various ways and I do not intend to be limited to the formation of this off-set portion prior to the time the pin is inserted in 90 position.

Having thus described my invention, I claim:

In a nut-lock, a screw-threaded part having a nut threaded thereon, a screw-threaded socket in the end of said part, the threads of which are opposite to the outside threads of said part, a studded head or cap adapted to be screwed into said socket, a perforation in 95 said head or cap, a series of perforations in said nut adapted to register with the perfo-

ration of the head or cap, a cotter-pin adapted to be inserted in the perforation in said head or cap and through one of the perforations of said nut, said cotter pin being offset at a point therein which lies between said head and said nut, substantially as and for the purpose specified.

In testimony whereof, I have hereunto set my hand this 17th day of January, 1908.

CHARLES S. NORRIS.
